UNITED STATES PATENT OFFICE

2,589,832

HAIR CURLER

Delia D. Loewenstein, Kearney, Nebr.

Application September 14, 1949, Serial No. 115,700

3 Claims. (Cl. 132—40)

1

The present invention relates to hair curlers and more particularly to devices for winding the hair into curls and holding the curls while the hair sets.

One of the objects of the present invention is to provide a simple, efficient and inexpensive device for curling hair.

Another objective is to provide a hair curler in which the curl may be wound in either direction from the scalp toward the ends of the hair.

Another objective is to provide a hair curler with which curls may be formed close to the scalp.

Another objective is to provide a hair curler which will hold the hair in curled position during setting without crimping.

A further objective is to provide a hair curler which will wind curls without pulling or binding.

These and other objects and advantages reside in novel features of construction, arrangement and combination of parts as will hereinafter be more fully set forth and pointed out in the following specification and claims.

Referring to the drawing:

Figure 1 is a plan view of my improved hair curler with parts broken away.

Figure 2 is a side elevation of my hair curler.

Figure 3 is a section taken on line 3—3 of Figure 1.

Figure 4 is a perspective view of my hair curler showing how a curl is wound thereon.

Figure 5 is an exploded view of my hair curler.

In the embodiment illustrated in the drawing, my hair curler consists of a thin, flat, circular body portion 10 having a cylindrical central column or stud 11. The body portion 10 is provided with a large notch 13 which extends inward from the periphery. This notch 13 preferably has a wide mouth to facilitate the insertion of a strand of hair. The body portion 10 is preferably solid so that any hair curling or waving solution is kept from touching the scalp. As shown in Figure 3, the body portion 10 is slightly cupped about the column or stud 11 and is preferably provided with an upturned edge or rim 14.

A sleeve 15 is rotatably mounted on the column or stud 11 and has an outwardly and downwardly cupped disc 16 at its lower end. This disc 16 fits within the rim 14 of the body portion 10 and is provided with perforations 17 and a notch 18 extending inwardly from its periphery. The notch 18 has a relatively narrow mouth and the side walls of the notch slope sharply away from the mouth so that there is a little or no tendency for the hair to slip out of the notch 18 as the

2

curl is being wound. It will be seen from Figure 3 that because of the concavity of the facing surfaces of the body portion 10 and disc 16, there is a space between the body portion and disc 5 which diminishes from the column or stud 11 outward toward the edge of the disc 16.

The sleeve 15 has an enlarged central bore 19 which terminates at a shoulder 20. A cap 21 extends over the end of the column or stud 11, 10 within the bore 19 and is firmly secured on the top of the column or stud 11, preferably by means of a suitable adhesive. A coil spring 22 acts between the cap 21 and shoulder 20 to urge the sleeve 15 and disc 16 toward the body portion 10. The end of the sleeve 15 remote from the disc 16 is provided with a flange 23 so that it may conveniently be turned or adjusted.

In forming a curl with my improved hair curler, the sleeve 15 and disc 16 are adjusted 20 until the notches 13 and 18 are in alignment as shown in Figures 1 and 2. A strand of hair to be curled is drawn through the notches 13 and 18 and the sleeve 15 and disc 16 are rotated relative to the body portion 10 and column 11 to 25 wind the strand of hair about the column. The sleeve 15 and disc 16 may be turned in either direction to provide either right-hand or left-hand curls. When the curl is wound, the sleeve 15 is released and the spring 22 causes the curl to be gripped between the body portion 10 and disc 16 without crimping and thus holds the curl against unwinding. By continuing to rotate the sleeve 15 and disc 16 until the ends of the hair 30 disappear through the notch 18, all of the hair 35 is wound on the column or stud 11 and the hair is curled outward to its ends.

Because the body portion 10 is thin, the curl may be wound very close to the scalp and is wound from the scalp outward rather than from 40 the ends inward as is the case in most present day curlers. Very often the hair being curled is wet either with water or some curling or waving solution and the perforations 17 permit and facilitate rapid drying.

45 My improved hair curler may be made of any suitable material such as metal, wood or plastic but I prefer to form the curler of plastic which is light, strong and impervious to the usual hair waving solutions. Such light curlers will not pull 50 the hair while the curl is setting.

From the foregoing, it will be apparent that I am able to attain the objects of my invention and provide a simple, effective hair curler capable of forming curls close to the scalp, holding the hair in curled condition without crimping and

permitting the curled hair to dry and set in curled condition. The foregoing specification and the drawing describe and illustrate one form of my hair curler and various modifications and changes may be made in my improved hair curler without departing from the spirit of my invention or the scope of the appended claims.

I claim:

1. A hair curler comprising a member having a concave surface and having a notch extending inward from its periphery, a column fixed to said member and projecting from said concave surface, a sleeve rotatably mounted on said column, a disc secured to said sleeve adjacent said member, said disc having a concave surface facing said member and having a notch extending inward from its periphery, said sleeve having an enlarged internal bore surrounding said column, a projection on the end of said column remote from said member, and a coil spring surrounding said column within said bore and engaging said projection and said sleeve for urging said disc toward said member. 25
2. A hair curler comprising, a pair of disclike members having opposed facing surfaces and each having a hair receiving notch extending inwardly from its peripheral edge; a column fixed to one of said disc-like members; a sleeve fixed

to the other of said disclike members, said sleeve having an internal bore, a portion of which is adapted to slidably and rotatably fit over said column; a stop on the outer end of said column; and spring means coiled around said column between said stop and a portion of said bore for yieldingly urging said opposed surfaces together.

3. A hair curler as defined in claim 2 in which the facing surfaces of said member and said disc are concave.

DELIA D. LOEWENSTEIN.
